Attorney.

UNITED STATES PATENT OFFICE.

CHRISTOPH LEFFLER, OF BRUNSWICK, GERMANY.

VALVE-REGULATING DEVICE.

Application filed August 23, 1921. Serial No. 495,559.

To all whom it may concern:

Be it known that I, CHRISTOPH LEFFLER, a citizen of the German Empire, residing at Brunswick, Germany, have invented certain new and useful Improvements in Valve-Regulating Devices (for which I have filed an application in Germany, July 5, 1920), of which the following is a specification.

My invention relates to electric regulating devices for prime-movers, such as water- and steam-turbines and more particularly to a device of the type having a contact slide controlled by a centrifugal governor, such slide not taking part in the rotation of the driven shaft and operating by the aid of an electric current generated by the prime-mover a control motor which then adjusts the admission valve for the driving agent of the prime-mover.

In the drawings affixed to this specification and forming part thereof, a device embodying my invention is shown diagrammatically by way of example.

Referring to the drawings upon a shaft *a* continuously rotated by a prime-mover is arranged a centrifugal governor *b*, which is adapted to move a sleeve *c* along the shaft *a*. A contact slide *d* is connected with this sleeve *c* in such a manner that the slide takes part in the reciprocating movement of the sleeve *c*, but not in its rotation. To this end the sleeve *c* is provided with a flanged disc *e* which rotates freely within a recess *f* of the contact slide *d*.

The electric current from the three wires *g*, *h*, *i* of the supply system passes across this contact slide *d* to a three phase or continuous current motor *k*, which, when supplied with current, performs a small angular motion only in one direction or the other and thereby opens or closes the admission valve controlling the driving agent.

If owing to a drop in the number of revolutions of the shaft *a* the sleeve *c* moves towards the left, the contact slide *d* will touch the contacts *l* and *l'*, so that the current in the conductors *g*, *i* passes through the wires *g'*, *i'* into the control motor *k*.

In the other end position of the sleeve *c* the contacts *l'*, *l* make connection between the branch wires *g''*, *i''* of the supply conductors *g*, *i* and the wires *g'''*, *i'''* which lead to the control motor *k*. The control motor *k* is thus started in the two end positions of the contact slide *d* in one or the other di-

rection, whereby the admission valve for the driving agent is controlled.

In order to avoid that while the contact slide *d* approaches the contacts *l*, *l'* or *l''*, *l'''*, a contact be established by a trifling motion 60 of the slide and in order further to avoid bad contact, brake springs *n*, *n'*, which have a clamping effect, are so disposed with relation to the contact slide *d*, that they detain the slide when moved by the governor 65 *b* until it is able to perform a comparatively long stroke, which after having overcome the brake resistance allows it to make good contact with ample surfaces upon the contacts *l*, *l'* or *l''*, *l'''*.

In order to prevent the contact from being maintained too long, once the regulation contacts have been reached, the contact slide *d* is withdrawn immediately after contact has been made with the stationary contacts *l*, *l'* or *l''*, *l'''* into an inoperative position. This is effected by aid of electro-magnets *o*, *o'*, which by the contacting of the contacts *p*, *q* or *p'*, *q'* and the closing of a circuit *t* or *t'* attract pendulums *r* or *r'*. 80 The lower ends of these pendulums engage projections *s* or *s'* upon the slide and tend to push the contact slide *d* back so that the contact with the contacts *l*, *l'* or *l''*, *l'''* is quickly broken again, if the fluctuations in the 85 number of revolutions of the driven shaft *a* are only insignificant. On the other hand if the speed of the shaft *a* drops considerably or very much exceeds a predetermined value, the power of the electro-magnets *o*, *o'* does 90 not suffice to detach the contact slide *d* from the contacts *l*, *l'* or *l''*, *l'''*. In this case an adjustment of the position of the admission valve for the driving agent takes place in correspondence with the variations in the 95 number of revolutions of the centrifugal governor.

It will be obvious that the details of the apparatus may be varied without departing from the spirit of the invention.

I claim:

1. In a device of the kind described in combination, a shaft, a centrifugal governor operatively connected with said shaft, a contact slide adapted to be imparted a reciprocating motion by said governor, electric means for adjusting the admission valve for the medium serving to drive said shaft, operative connection between said electric means and said contact slide for closing the 110

circuit for actuating the admission valve and other electric means for pulling back the contact slide and for interrupting the circuit.

- 5 2. In a device of the kind described in combination, a shaft, a centrifugal governor operatively connected with said shaft, a contact slide adapted to be imparted a reciprocating motion by said governor, electric 10 means for adjusting the admission valve for the medium serving to drive said shaft, operative connection between said electric means and said contact slide for closing the

circuit for actuating the admission valve, other electric means for pulling back the contact slide and for interrupting the circuit and brake springs adapted to restrain the reciprocating movement of said slide so as to prevent insufficient contact-making of said slide. 15
